[57] CLAIM

The ornamental design for an ice chest, as shown and described.

DESCRIPTION

FIG. 1 is a perspective view of an ice chest showing my new design from the front, top and right end, with its handle and its removable, reversible lid closed;

FIG. 2 is a top plan view thereof;

FIG. 3 is a left end elevation view thereof;

FIG. 4 is a front elevation view thereof;

FIG. 5 is a right end elevation view thereof with its handle extended in a position of use;

FIG. 6 is a perspective view thereof in a position of use, with its reversible lid open; and,

FIG. 7 is a perspective view thereof in a position of use, with its lid having been turned upside down and placed on the body of the ice chest in a closed position.

*Fig. 1**Fig. 2*

*Fig. 3**Fig. 4**Fig. 5*
